SHOE MACHINE

Karl Engel, Swampscott, Mass., assignor to United
Shoe Machinery Corporation, Paterson, N. J., a
corporation of New Jersey

Application April 24, 1936, Serial No. 76,218

29 Claims. (Cl. 12—7)

The present invention relates to machines for use in manufacturing boots and shoes and is herein illustrated in its application to the manufacture of pre-welted shoes, that is shoes in the manufacture of which a welt is stitched to the upper before the upper is lasted. The invention is illustrated as embodied in a bed lasting machine of the type disclosed in United States Letters Patent No. 1,018,477, granted February 27, 1912 on an application of Matthias Brock. While the invention is herein illustrated in its application to the manufacture of pre-welted shoes, it is to be understood that the invention is not limited in its scope to machines for use in the manufacture of such shoes but is applicable, in certain of its aspects, to machines for use in the manufacture of other types of shoes.

Objects of the present invention are to facilitate and improve the manufacture of shoes and more particularly to improve bed lasting machines for operating on pre-welted shoes such, for example, as the machines illustrated in United States Letters Patent No. 2,042,518, granted June 2, 1936 upon my application and application Serial No. 43,567, filed October 4, 1935 in the name of René E. Duplessis.

In the machine illustrated in my copending application above referred to there are provided, in combination with the usual toe-lasting wipers and heel-lasting wipers, side-lasting wipers having wiping movement widthwise only of a shoe in the machine. It is now proposed to provide side wipers having wiping movement lengthwise as well as widthwise of the shoe and accordingly a feature of the invention consists in the combination with end-embracing lasting wipers constructed and arranged for wiping movement lengthwise of a shoe in the machine and widthwise of the shoe, of side-lasting wipers constructed and arranged for wiping movement by the end-lasting wipers both lengthwise and widthwise of the shoe, and means for supporting those ends of the side wipers remote from the end wipers and for guiding their wiping movements. In the illustrated machine the side-lasting wipers are supported by the heel wipers and guided by connections to the toe-lasting wipers. The illustrated construction provides a combined forward and widthwise movement of the side-lasting wipers which is particularly effective for lasting the shank portion of the shoe.

For supporting an inverted upper in the machine there is provided, in accordance with a further feature of the invention, a member extending heightwise of the upper for engagement

with the upper in the region of the apex of the angle defined by the interengaging surfaces of the welt and upper and hereinafter referred to as the welt crease. For engaging the upper-attaching face of the welt to position the welt for attachment to an outsole there is provided welt engaging means which in the illustrated machine is the toe lasting wipers. For effecting relative movement of the upper-supporting member and the toe-lasting wipers thereby to bend the welt of the supported upper into sole-attaching position there is provided means which in the illustrated machine is operated by the downward movement of a depressor which forces the forepart of a last into the supported upper.

In order to insure uniform wiping of the welted margin of the upper over the last bottom there are provided, in accordance with a further feature of the invention, shoe-engaging members constructed and arranged to be operated by closing movements of end-lasting wipers to centralize the last relatively thereto, said members, in the illustrated machine, being operated by the advancement of the heel wipers. The shoe-engaging members perform their function without limiting the overwiping movement of the heel wipers. As herein illustrated, the shoe-engaging members comprise resilient plates having the general shape of the heel portion of a shoe and secured to the heel wipers adjacent to their interengaging edge faces, the forward portions of said plates being left free to flex as the heel wipers last the heel portion of a shoe in the machine.

These and other features of the invention will now be described with reference to the accompanying drawings and will be pointed out in the appended claims.

In the drawings,

Fig. 1 is a front elevation of the top portion of a bed lasting machine embodying my invention;

Fig. 2 is a front elevation of the bottom portion of the machine;

Fig. 3 is a plan view of the machine with an upper supported therein;

Fig. 4 is a plan view illustrating particularly the lasting wipers;

Fig. 5 is a detail view in front elevation illustrating the forepart-supporting assembly;

Fig. 6 is a view similar to Fig. 5 showing in connection with the forepart-supporting assembly the fingers which guide the forepart of the last during its depression into the upper;

Fig. 7 is a detail view in front elevation showing the upper part of the upper-supporting member illustrated in Figs. 5 and 6, together with the

Fig. 12 is a plan view of the wipers in a different position from that illustrated in Fig. 10;

Fig. 13 is a plan view showing the wipers fully 15 advanced and a pre-welted upper supported thereon in lasted position, and

Fig. 14 is a detail view in front elevation illustrating particularly the arrangement of the toe wipers and the forepart-supporting plate when 20 the wiper is in its advanced position.

In common with prior machines of the illustrative type, the machine illustrated in the drawings is provided with toe-lasting wipers 23 (Fig. 4) and heel-lasting wipers 22 and in common with 25 the machine illustrated in my copending application and in the application filed by René E. Duplessis both above referred to the machine herein illustrated is provided with side-lasting wipers 24 and with a series of last-guiding members or fingers 26 (Fig. 1) for guiding the forepart of a last as it is depressed into the forepart of an upper in the machine by a depressor member 28 which is constructed and operated the same as the last depressor of the Duplessis machine. As illustrated in Fig. 6, the last-guiding fingers 26 are made straight throughout their 30 entire length in order to permit downward movement of the last and upper relatively to the fingers after the last has been positioned in the upper. As illustrated in Figs. 1 and 3, the last-guiding fingers are mounted on a yoke 30 which is mounted for vertical swinging movement on a slide 32 mounted in the toe head 34 for movement toward and from the toe end of a shoe in the 35 machine. The finger assembly is moved away from the toe end of the shoe by a spring 36 one end of which is connected to a pin 38 in a hollow boss 40 extending upwardly from the slide 32 and the other end of which is connected to a 40 hook 42 secured to a bracket 44 on the toe head. The spring 36 holds the slide 32 against a stop pin 46 mounted in a bracket 48 on the toe head. For swinging the finger assembly from its elevated 45 position in Fig. 1 to its operative position in Fig. 6 a handle 50 is secured to the arm 52 which carries the yoke 30. For positioning the fingers heightwise thereof relatively to the upper in their 50 operative position, as seen in Fig. 6, a stop screw 54 is mounted in the central portion of the yoke 30 and arranged to engage the top plate 56 of the toe head. The finger assembly is supported in its retracted position, as illustrated in Fig. 1, by a spring-pressed pin 58 mounted at the upper end of a short arm 60 extending upwardly from the arm 52. When the finger assembly is in its 55 retracted position the pin 58 engages the depressor member 28 and thereby holds the finger assembly against downward movement. The pin 58 is manually retracted to permit downward movement of the finger assembly and in order to 60 facilitate manual retraction of the pin it is provided with a knob 62. As the finger assembly moves downwardly the pin 58 slides against the front face of the depressor member 28 and during 65 the latter part of the advancement of the

depressor 28 the depressor moves away from the pin 58 and the pin springs back into its initial position. During the retraction of the depressor the pin 58 is engaged thereby and the finger assembly is returned to its retracted position. The 5 mechanism for operating the depressor 28, which is substantially the same as in the machine of the Duplessis application above referred to, comprises a treadle 63 (Fig. 2), and a vertical slide 65 (Fig. 1) mounted in the toe head 34 and provided 10 with connections, including an extensible link 73, to the treadle 63. At its upper end the slide 65 is provided with a crosshead 67 having in its front face a horizontal groove within which travels a roll 69 (Fig. 3) carried by a bracket 71 on the hub 15 of the last depressor 28.

Referring now to Fig. 3, the heel portion of a prewelted upper such, for example, as the upper 64 illustrated therein, is supported by its welt upon the heel wipers 22 and clamped against the 20 wipers by a clamping plate 66, which is secured to the free end of a vertically swinging arm 68 carried by the heel head 70. The heel clamp and its operating mechanism is the same as in the machine of the Duplessis application above referred to. The operating mechanism for said clamp includes a treadle 72 (Fig. 2) which is depressed after the plate 66 has been manually advanced into position to engage the welt of the upper 64, the depression of said treadle operating to impart clamping pressure to the plate 66 through connections including a treadle-actuated rod 74 (Fig. 1), a vertical slide 76 carried by the heel head, a bell crank lever 78 arranged to be actuated by said slide, and operating connections (not shown) from the bell crank lever to the arm 68.

For supporting the forepart of the upper 64 the illustrated machine is provided with a toe post 80 (Fig. 6) having at its upper end a head 82 which has in plan view the general outline of the forepart of the upper. Secured to the curved wall of the head 82 is an upwardly extending plate 84 the upper edge of which engages the upper 64 in the welt crease. The toe post 80 is yieldingly supported on a horizontal arm 86 provided in the machine frame. The illustrated mechanism for supporting the toe post comprises a sliding pin 88 mounted in a hollow screw 89 extending downwardly from the toe post. The pin 88 extends upwardly from the screw 89 into a central bore in the toe post and engages at its upper end a spring 90 in said bore. The toe post 80 is slidably mounted in a vertical hole in an upwardly extending head 92 of a horizontal sliding rod 94 carried by a hollow dovetail slide 96 (Fig. 9) mounted in a dovetail groove in the bottom of the toe head 34. The sliding rod 94 is held against turning movement in said dovetail slide by a pin 98 extending upwardly into a slot 100 (Fig. 5) 60 extending lengthwise of the slide 96. For holding the toe post 80 against turning movement and thus positioning the plate 84 for the reception of the forepart of an upper the head 92 of the sliding rod 94 is provided with a pin 102 the 65 inner end of which extends into a vertical groove 104 in the toe post. As illustrated in Figs. 5 and 8, the dovetail slide 96 is provided with parallel vertical ears 106 which engage slabbed-off portions 108 at opposite sides of the head 92 of the 70 sliding rod 94. Projecting outwardly from one of the ears 106 is a boss 110 which carries a screw 112 which has secured between clamping nuts 114 at one end thereof a stop plate 116 which, as illustrated in Fig. 8, is arranged to engage the 75

head 92 of the slide 94. The head 92 is urged against the stop plate by a compression spring 118 (Fig. 5) one end of which engages the toe head and the other end of which is seated in a 5 socket in the head 92. The end of the screw 112 opposite the stop plate 116 provides a stop for locating the dovetail slide 96 by engagement with the toe head, the dovetail slide being held in its 10 position illustrated in Fig. 5 with the screw 112 in engagement with the toe head by a tension spring 119 (Fig. 1) which is substantially stronger than the spring 118. The stop plate 116 is adjusted endwise of the screw 112 to determine the initial position of the upper-supporting plate 15 84 lengthwise of a shoe in the machine, or if desired, the screw 112 together with the stop plate 116 may be adjusted by turning the screw in the boss 110. The preferred adjustment, as illustrated in Figs. 10 and 12, is such that the wipers engage the plate 84 at an intermediate stage in their 20 advancement, and in their retracted positions are spaced from said plate sufficiently to permit upward movement thereof. The horizontal movement of the last-guiding fingers 26 by the spring 25 36 after said fingers have been positioned within the upper 64 moves the forepart-supporting assembly forwardly of the upper 64 from its position in Fig. 5 to its position in Fig. 6, the extent of said movement being indicated in Fig. 6 by the 30 separation of the head 92 from the stop plate 116. During the forward movement of the forepart supporting assembly the heel end of the upper is held from forward movement by the clamp 66 and consequently the upper is drawn or tensioned 35 lengthwise thereof and held under tension by the fingers 26 for the reception of a last. It will be understood that the desired operation of the finger assembly 26 and the forepart-supporting assembly requires an accurate adjustment of the 40 toe head relatively to the heel head for the size of shoe to be operated upon.

In its position in Fig. 6 the upper 64 is supported with its welted margin substantially above the plane of the toe wipers 20. The upper is 45 positioned for the operation of the toe-lasting wipers 20 thereon by downward movement of the forepart of the upper and the forepart-supporting assembly by the latter part of the downward movement of the depressor 28, which movement 50 forces the forepart of the last, together with the forepart of the upper and the forepart supporting assembly, downwardly into their positions illustrated in Fig. 7. The illustrated mechanism for effecting downward movement of the forepart-supporting assembly comprises a swinging arm 120 (Fig. 3) pivoted to a bracket 121 on the toe head and provided with an inwardly extending arm 122 which carries a screw 124 (Fig. 6) the lower end of which engages a plate 126 secured to and projecting outwardly from a base plate 127 provided in the head 82 of the toe post. The arm 128 is moved downwardly by the last depressor which, as illustrated in Fig. 3, is provided with a bracket 130 having a stop screw 128 which, as illustrated in Fig. 7, engages the upper edge face of the arm 120 during the latter part of the downward movement of the depressor, which movement is limited by the engagement of 65 a stop screw 129 (Fig. 1) with the yoke 30. As illustrated in Fig. 7, the adjustment of the stop screw 128 is such that the forepart-supporting assembly continues to move downwardly after the welt 132 of the upper 64 has flattened against 70 the toe wipers 20 thereby to bring the bottom 75

face of the last and the upper edge of the upper-supporting plate 84 into a position which permits overwiping movement of the toe wipers 20.

Referring now to Fig. 10, the illustrated machine is provided with side-lasting wipers 24 which operate on the shank and ball portions of a pre-welted upper by engagement with the upper in the region of the welt crease. In order to facilitate the introduction of the wipers 24 into the welt crease of an upper in the machine said 10 wipers are made of very thin material. The side wipers are supported upon the toe wipers 20 and the heel wipers 22 with their wiping edges substantially in alignment with the wiping edges of the toe wipers and the heel wipers. The side 15 wipers are moved lengthwise and widthwise of an upper in the machine by the heel wipers 22 through pivotal connections comprising headed screws 140 mounted alternatively in a series of tapped holes 142 in the heel wipers 22. Said 20 holes are arranged in lines extending lengthwise of an upper in the machine and afford adjustment of the side wipers for different sizes of uppers. The movements of the side wipers 24 by the heel wipers are guided and directed by 25 headed screws 144 projecting upwardly from the outer end portions of the toe wipers 20, respectively, and extending through slots 146 provided in the side wipers. In lasting pre-welted uppers 30 in the illustrated machine the rear part is lasted first in order to get a wiping action at the ball portion of the upper having a forward component of movement as indicated by the arrows on the side wiper plates in Figs. 9 and 11. It will be seen 35 that the direction of movement of the side wipers 24 is determined somewhat by the direction of the slots 146 provided therein, said slots, as illustrated in Fig. 9, being substantially parallel to the wiping edges of the side wipers. This 40 arrangement of the slots not only affords the desired wiping action of the side wipers but also provides a wiper assembly wherein the wiping edges of the toe wipers and side wipers are in alignment with each other at all times. 45

For supporting the heel portion of a last the illustrated machine is provided with a yielding heel support or post 148 (Fig. 1) provided with a flat head 150 on which the last is movable lengthwise and widthwise thereof to position it 50 relatively to the lasting wipers. For centering the heel portion of the last relatively to the heel wipers 22 said wipers are provided with a pair of resilient last-positioning members 152 (Fig. 10). Referring to Fig. 11 illustrating the last-engaging member extending downwardly from one of the heel wipers illustrated in Fig. 10, the illustrated last-engaging member comprises a resilient metal plate 154 secured to a block 156 extending downwardly from the wiper plate adjacent to that edge face of the wiper plate which 55 in the open position of the wipers, as illustrated in Fig. 10, coincides with the longitudinal median line of a shoe in the machine. The plate 154 is secured to the outer face of the block 156 60 and arranged perpendicularly to the under surface of the heel wiper. The plate 154 extends laterally and toward the toe wipers from the block 156 and has the general curvature of the wiping edge 158 of the heel wiper 22 but converges somewhat relatively to said wiping edge 70 and thus provides a construction wherein the end portion of the plate adjacent to the block 156 is spaced from the wiping edge 158 a distance somewhat greater than the overwiping move- 75

ment required for lasting pre-welted shoes while the opposite end portion of the last-engaging member is arranged with its last-engaging surface substantially in vertical alinement with the 5 wiping edge 158. The side face of the block 156 nearest to the wiping edge 158 of the heel wiper is arranged in alinement with the curved portion of the plate 154 and together with said curved portion of the plate is faced with a non-abrasive member or pad 160 which, as illustrated 10 in Fig. 11, comprises two layers of grain leather which are riveted together and secured to the plate 154 by means of a staple 162 the cross-bar of which lies between the two thicknesses of 15 leather and the legs of which extend through the outer thickness only and through suitable holes in the plate 154, the projecting ends of said staple being turned outwardly against the outer surface of said plate. Referring now to Fig. 10, 20 it will be seen that the illustrated last-positioning members 152 provide means for engaging the heel portion of an upper on its last during the closing movements of the heel wipers and thereby center the heel portion of the last relatively 25 to the wipers before the wipers move inwardly over the last bottom to perform the overwiping movement. The resilient plates 154 are strong enough to move the heel portion of the last into 30 a central position relatively to the heel wipers if the last is out of position but are sufficiently yielding to permit overwiping movement of the heel wipers with no appreciable increase in effort on the part of the operator.

35 It will be seen that the forepart of the last is centered relatively to the toe wipers 20 by the upper-supporting plate 84 which, as illustrated in Fig. 10, is centrally located relatively to the wipers, and as illustrated in Fig. 7, positions the last 40 relatively to the toe wipers for the overwiping operation.

In lasting pre-welted uppers in the illustrated machine the heel portion of an inverted upper is positioned on the heel wipers 22 and the back seam of the upper is brought into alignment with the adjacent ends of the wiping edges of the heel wipers. The heel clamp 66 is then brought into engagement with the sole-attaching face of the welt in order to secure the upper in position on the last. The toe head 34 is then adjusted, if necessary, to bring the forepart-supporting plate 84 into alignment with the welted margin of the forepart of the upper. The upper is then positioned on the plate 84 and the toe wipers 20 are brought into engagement with said plate, as illustrated in Fig. 6. The last-guiding fingers 26 are then swung downwardly from their position in Fig. 1 and during their downward movement a dog 166 carried by the finger assembly engages a stop or shoulder provided in a plate 168 on the top plate of the toe head. The dog engages the plate while the fingers 26 are above the supported upper and causes the finger assembly to move rearwardly of the upper during continued downward movement thereof in order to position the fingers for entrance into the upper. The dog 166 is pivoted to the arm 52 which carries the yoke 30 on which the fingers 26 are mounted and is yieldingly held by a spring 170 against a pin 172 on said arm. During the latter part of the downward movement of the finger assembly after the fingers have entered the supported upper a short pin 174 in the free end of the dog 166 engages the top of the plate 168 and provides a fulcrum point about

which the dog is swung to disengage it from the shoulder provided in the plate 168. After the dog has been disengaged from the shoulder the spring 36 moves the slide 32 and the finger assembly carried thereby forwardly of the upper into engagement with the interior of the welted margin of the upper at its toe end. Further movement of the slide 32 by the spring 36 moves the finger assembly, together with the upper-supporting assembly, forwardly of the upper, 10 said slide finally coming to rest against the stop screw 46. During such forward movement of the toe-supporting assembly the operator maintains engagement of the toe wipers 20 with the upper-supporting plate 84 in order to prevent the welt 132 from becoming positioned between the wiping edges of the toe wipers and the upper-supporting plate 84. After the finger assembly 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880

While the invention has been illustrated in its application to machines particularly adapted to the lasting of pre-welted shoes, it is to be understood that the invention is not thus limited in its scope, certain features of the invention relating to lasting machines generally. 50

Having thus described my invention, what I claim as new and desire to secure by Letters Patent of the United States is: 55

1. In a lasting machine, the combination with
end-embracing lasting wipers constructed and
arranged for wiping movement lengthwise of a
shoe in the machine and widthwise of the shoe,
of side-lasting wipers constructed and arranged
for wiping movement by the end-lasting wipers
both lengthwise and widthwise of the shoe, and
means for supporting those ends of the side wipers
remote from the end wipers and for guiding
their wiping movements. 65

2. In a lasting machine, the combination with end-embracing lasting wipers constructed and arranged for wiping movement forwardly of a shoe in the machine and widthwise of the shoe, of side-lasting wipers constructed and arranged for wiping movement by the end-lasting wipers both lengthwise and widthwise of the shoe, and means for supporting those ends of the side wipers remote from the end wipers and for guiding

- their wiping movements and for imparting wiping movements thereto widthwise of the shoe.
3. In a lasting machine, the combination with two pairs of end-lasting wipers for lasting, respectively, the opposite end portions of a shoe in the machine, of side-lasting wipers constructed and arranged for wiping movement both lengthwise and widthwise of the shoe by one pair of end-lasting wipers and constructed and arranged for wiping movement widthwise only of the shoe by the other pair of end-lasting wipers.
4. In a lasting machine, the combination with heel-embracing lasting wipers constructed and arranged for movement forwardly of a shoe in the machine and widthwise of the shoe, of a pair of toe-lasting wipers, and a pair of side-lasting wipers constructed and arranged for movement forwardly of the shoe and widthwise thereof by the heel wipers and constructed and arranged for movement widthwise of the shoe by the toe wipers.
5. In a lasting machine, the combination with heel-lasting wipers constructed and arranged for wiping movement forwardly of a shoe in the machine and widthwise of the shoe and forepart-lasting wipers, of side-lasting wipers, the rear portions of which are pivoted to the heel wipers and the forward portions of which are supported on the forepart wipers, and connections between the forepart wipers and the side wipers whereby the forward movement of the side wipers is directed and whereby movement of the forepart wipers widthwise of the shoe is imparted to the side wipers.
- 35 6. In a lasting machine, the combination with heel-lasting wipers constructed and arranged for wiping movement forwardly of a shoe in the machine and widthwise of the shoe and forepart-lasting wipers, of a pair of wipers for lasting that portion of an upper between the tip line and the heel, the rear portions of said wipers being pivoted to the heel wipers and their forward portions having pin-and-slot connections to the forepart wipers.
- 45 7. In a lasting machine, the combination with end-lasting wipers, of shoe-engaging members constructed and arranged to be operated by closing movements of the wipers to centralize the last relatively to the wipers without limiting the over-wiping movement of the wipers.
- 55 8. In a lasting machine, the combination with end-lasting wipers, of shoe-engaging members constructed and arranged to be operated by closing movements of the wipers to centralize the last before the wipers begin their overwiping movement and to hold the last centralized relatively to the wipers during their overwiping movement.
9. In a lasting machine, the combination with end-lasting wipers, of resilient plates carried by and extending downwardly from the wipers and arranged to be operated by the wipers to centralize an end portion of the last relatively to the wipers.
- 65 10. In a lasting machine, the combination with end-embracing lasting wipers, of resilient plates extending downwardly from the wipers and secured to the wipers near the adjacent edges of the wipers, said plates having the general shape of an end portion of a shoe and being arranged to engage the shoe during the advancement of the wipers before the wipers begin their overwiping movement.
11. In a machine for use in the manufacture of pre-welted shoes, a member extending height-
- wise of an inverted pre-welted upper in the machine for engagement with the upper in the region of the welt crease, a member constructed and arranged to engage the upper-attaching face of the welt and to position the welt for attachment to an outsole, and means for effecting relative movement of said members and an upper mounted thereon thereby to bend the welt into sole-attaching position.
12. In a machine for use in the manufacture of pre-welted shoes, a member extending heightwise of an inverted pre-welted upper in the machine, a member extending at right angles to the height of the upper for engagement with the upper-attaching face of the welt, and means constructed and arranged to operate against the bottom of a last in the supported upper thereby to move the upper together with the first-mentioned member heightwise of the upper thereby to bend the welt upon the welt-engaging member into outsole-attaching position.
13. In a machine for use in the manufacture of pre-welted shoes, means for supporting an inverted pre-welted upper comprising a vertical plate constructed and arranged to engage the upper within the welt crease, a horizontal plate for engaging the upper-attaching face of the welt and bending the welt into sole-attaching position, and a depressor for pressing a last into the supported upper and for moving the upper and its supporting plate heightwise thereof relatively to the welt-engaging member thereby to cause the welt to be bent into sole-attaching position.
14. In a machine for use in the manufacture of pre-welted shoes, an upper-supporting member extending heightwise of an inverted upper in the machine, a welt-engaging member for supporting the welt for the reception of a sole, yielding means operating on the upper-supporting member to position the welt above its supporting member, and means for effecting downward movement of the upper and its support thereby to bend the welt on its supporting member into sole-attaching position.
15. In a machine for use in the manufacture of pre-welted shoes, lasting wipers, means extending heightwise of an upper in the machine for supporting the upper above its lasting position by engagement with the upper in the region of the welt crease, and means for effecting downward movement of the upper together with its supporting means thereby to locate the upper in lasting position and to bend the welt against the wipers into sole-attaching position.
16. In a machine for use in the manufacture of pre-welted shoes, the combination with forepart-lasting wipers of means for supporting the forepart of an inverted pre-welted upper comprising a plate extending heightwise of an upper in the machine and curved to conform to the periphery of the forepart of a last to be positioned in the upper, yielding means operating on said supporting plate to hold the upper thereon above its lasting position, a depressor constructed and arranged to press the forepart of a last into the supported upper, and means operated by continued downward movement of the depressor after the last has been positioned in the upper to move the upper-supporting member downwardly to permit the upper to be located in lasting position.
17. In a machine for lasting pre-welted uppers, the combination with end-lasting wipers of means for supporting an end portion of an

inverted pre-welted upper comprising a plate having the curvature of the end portion of the upper and arranged to extend heightwise of an upper in the machine, said plate being movable heightwise of the upper and yieldingly supported at the limit of its upward movement with the end portion of the upper thereon located above its lasting position, a depressor for forcing a last into the upper, and a member constructed and arranged to move downwardly with the depressor and to depress the upper-supporting plate after the last has been positioned with the upper thereby effecting further downward movement of the last and upper to locate the upper in lasting position and to bend the welt against the lasting wipers into sole-attaching position.

18. In a lasting machine, the combination with end-lasting wipers, of shoe-engaging members constructed and arranged to be operated by closing movements of the wipers to centralize the last relatively to the wipers, and means operating at the opposite end of the shoe to centralize the last relatively to the wipers.

last relatively to the wipers.

19. In a lasting machine, the combination with
25 end-lasting wipers, of shoe-engaging members
constructed and arranged to be operated by
closing movements of the wipers, and a member
extending heightwise of the shoe at its opposite
30 end and arranged to engage opposite side por-
tions of the shoe thereby to centralize that end
of the last relatively to the wipers.

20. In a lasting machine, the combination with
end-lasting wipers, of an end-embracing member
extending heightwise of a shoe in the machine
35 and arranged to engage the periphery of the
shoe thereby to centralize the shoe relatively to
the lasting wipers, and means for centralizing the
opposite end of the shoe relatively to the wipers
comprising shoe-engaging members constructed
40 and arranged to be operated by closing move-
ments of the wipers.

21. In a machine for use in the manufacture of pre-welted shoes, an upper-supporting member extending heightwise of a pre-welted upper
45 in the machine for engagement with the upper in the region of the welt crease, said member being constructed and arranged for movements heightwise of the upper and lengthwise of the upper to position the upper relatively to means
50 for operating thereon.

30 22. In a machine for use in the manufacture
of pre-welted shoes, an upper-supporting mem-
ber extending heightwise of a pre-welted upper
in the machine for engagement with the upper
55 in the region of the welt crease, said member be-
ing constructed and arranged for movements
heightwise of the upper and lengthwise of the
upper to position the upper relatively to means
for operating thereon, means for effecting return
60 lengthwise movement of said member, and a stop
for limiting such return movement and thus posi-
tioning said member for the reception of an
upper.

23. In a machine for lasting pre-welted shoes, end-lasting wipers, an end-embracing member extending heightwise of a pre-welted upper in the machine and arranged to support the upper by engagement therewith in the region of the welt crease, yielding means operating on said member 65 to hold the upper above the plane of the wipers, yielding means for positioning said member lengthwise of the upper, and means for moving 70 said member downwardly to position the welted margin of the upper in the plane of the wipers.

75 24. In a machine for lasting pre-welted shoes.

end-lasting wipers, an end-embracing member extending heightwise of a pre-welted upper in the machine and arranged to support the upper by engagement therewith in the region of the welt crease, yielding means operating on said member to hold the upper above the plane of the wipers, yielding means operating on said member to position the upper rearwardly thereof from its lasting position, a depressor for forcing a last into the supported upper, and means operated by said depressor for moving said member downwardly to position the welted margin of the upper in the plane of the wipers. 5 10

25. In a machine for lasting pre-welted shoes, end-lasting wipers, an end-embracing member 15 extending heightwise of a pre-welted upper in the machine and arranged to support the upper by engagement therewith in the region of the welt crease, yielding means operating on said member to hold the upper above the plane of the 20 wipers, yielding means for positioning said member lengthwise of the upper, a stop for determining the operative position of said member lengthwise of the upper, and yielding means for holding said member in operative position. 25

26. In a machine for lasting pre-welted shoes, end-lasting wipers extending heightwise of an inverted pre-welted upper in the machine and arranged to support the upper by engagement therewith in the region of the welt crease, yielding means operating on said supporting member to hold the upper above the plane of the wipers, yielding means operating on said member to urge it lengthwise of the upper from the position in which it is located when the upper is arranged for the lasting operation, a stop for determining the position lengthwise of the upper in which the upper supporting member is arranged to position the upper for the lasting operation, and means for holding the supporting member against said stop. 40

27. In a machine for lasting pre-welted shoes, toe lasting wipers, a forepart-embracing member extending heightwise of an inverted pre-welted upper in the machine and arranged to support the upper by engagement therewith in the region of the welt crease, heel-lasting wipers, yielding means for moving said supporting member toward the heel wipers from the position of said member wherein the forepart of the upper supported thereon is positioned for the lasting operation, means constructed and arranged to engage the interior of the welted margin of the toe end of the upper, and to move the forepart of the upper together with the forepart support forwardly of the upper to position the upper for the lasting operation.

28. In a machine for lasting pre-welted shoes, toe lasting wipers, a forepart-embracing member extending heightwise of an inverted pre-welted upper in the machine and arranged to support the upper by engagement therewith in the region of the welt crease, heel-lasting wipers, yielding means for moving said supporting member toward the heel wipers from the position of said member wherein the forepart of the upper supported thereon is positioned for the lasting operation, means constructed and arranged to engage the interior of the welted margin of the toe end of the upper and to move the forepart of the upper together with the forepart support forwardly of the upper to position the upper for the lasting operation, yielding means operating on said forepart supporting member to hold the upper above the plane of the wipers, and means for moving said member downwardly to position the 75

welted margin of the upper in the plane of the wipers.

29. In a machine for lasting pre-welted shoes, toe lasting wipers, a forepart-embracing member 5 extending heightwise of an inverted pre-welted upper in the machine and arranged to support the upper by engagement therewith in the region of the welt crease, heel-lasting wipers, yielding means for moving said supporting member to 10 ward the heel wipers from the position of said member wherein the forepart of the upper supported thereon is positioned for the lasting operation, means constructed and arranged to engage

the interior of the welted margin of the toe end of the upper and to move the forepart of the upper together with the forepart support forwardly of the upper to position the upper for the lasting operation, yielding means operating on said 5 forepart-supporting member to hold the upper above the plane of the wipers, a depressor for forcing a last into the supported upper, and means operated by said depressor for moving the forepart of the upper together with its support- 10 ing member downwardly to position the welted margin of the upper in the plane of the wipers.

KARL ENGEL.
